UNITED STATES PATENT OFFICE.

DON S. WILLEY, OF CHICAGO, ILLINOIS.

CENTRIFUGAL PUMP.

Application filed January 28, 1922. Serial No. 532,472.

To all whom it may concern:

Be it known that I, DON S. WILLEY, a citizen of the United States, and a resident of Chicago, in the county of Cook and State 5 of Illinois, have invented certain new and useful Improvements in Centrifugal Pumps, of which the following is a specification.

This invention relates to improvements in centrifugal pumps such as used in caissons 10 or mines, and has for its principal object to provide an improved pump of the character described and a new method of operating the same, whereby the pump may be primed when starting its operation, and 15 may be maintained in operative condition and free from clogging by sand or the like during temporary periods of inoperation.

The invention may best be understood by reference to the accompanying drawing, illustrating one embodiment of my invention, in which:

Fig. 1 is a view of a centrifugal pump, constructed in accordance with my invention and installed in a mine,

Fig. 2 is an enlarged view in cross section of the foot valve forming a part of the centrifugal pump shown in Fig. 1, and

Fig. 3 is a view in cross section of a modified form of foot valve, illustrating another application of my invention.

Centrifugal pumps are often used for pumping fluid in which a large amount of sediment such as sand is held in suspension, but when pumping is discontinued for a 35 short period, the matter held in suspension tends to precipitate and often clogs either the pump itself, or the foot valve through which the fluid is drawn, so as to render the pump useless until cleaned. This is particularly objectionable when such a pump is used at a considerable depth, as in mines, 40 caissons, or under similar conditions, where cleaning the pump entails considerable labor, together with a loss in time.

In the drawing, one form of centrifugal pump, used in mines or the like, is shown to illustrate my invention. This pump comprises a cage 10, carrying a centrifugal pump 11 of any approved design mounted 45 to rotate on a vertical axis, and having operative connection with an electric motor 12.

The cage 10 is adapted to be lowered into the mine by any suitable suspension means 50 such as a cable 13 and reel 14 mounted on a support 15. Handles 16, 17 or their

equivalents may be used for operating said reel. The pump 11 is provided with an axially disposed, downwardly extending inlet pipe 17, having a foot valve 18 at the lower end thereof. A discharge pipe 19 extends upwardly from the pump to the surface of the ground, from where the discharged fluid may be distributed as desired. The foot valve 18 consists in a check valve 65 of any suitable construction, such as a ball valve having a casing 20 provided with a plurality of inlets 21, 21 at its lower end for ingress of the fluid, a partition 22 having an orifice 23 therethrough, and a ball 24 retained in a suitable cage 25 adapted to be seated over said orifice.

When a pump of the type illustrated is first lowered into pumping position, it is necessary to "prime" it, that is to say, the 75 pump and intake tube 17, must be filled with fluid before it will operate. After the pump is started it will lift fluids having a heavy content of solid matter, such as sand, as long as it is operated continuously. It is often desirable, however, to discontinue 80 pumping for various periods of time without raising the pump from the mine, and when this is done, it will be seen that the sand, sediment, etc., normally held in suspension in the fluid, tends to settle. The solid matter in the discharge tube 19, will settle into the pump 11 and that in the intake pipe 17 will settle into the check valve 18, and after 85 a short time, either or both, are choked or 90 clogged so as to render the pump useless until the pump is cleared.

In order to overcome the objectionable feature just described, I provide an auxiliary fluid pipe 30, connected to the foot valve 95 18, and communicating with a series of jets or orifices 31, 31 adjacent the seat of the ball check 24, and directed inwardly and upwardly toward said ball, as shown. Any number of such jets 31, 31 may be provided. 100 In the preferred form illustrated, two jets are shown arranged oppositely to each other, and connected by an annular passage 32 formed in the partition 22 of the valve casing.

The fluid pipe 30 is connected at its upper end to a means for supplying pressure, such as a pump 34, or its equivalent, operated independently of the centrifugal pump 11, so as to supply a stream of fluid to the 110 centrifugal pump when it is desired to prime the latter, and at all times that said

centrifugal pump is not in operation. The fluid from the pipe 30 is injected at a point where it will flush the foot valve, and passes up through the inlet pipe 17, pump 11, and 5 discharge pipe 19, so as to prime the pump, and thereafter, when pumping is temporarily discontinued, the sand within the pump, is kept in constant agitation so as to be prevented from settling. The pump may 10 thus be maintained in operative condition at all times, ready for immediate resumption of work. Furthermore, in case of a slight leak in the foot valve, which might ordinarily allow sufficient fluid to escape so as 15 to require priming, my improved attachment keeps the pump fully primed and ready for instant operation.

In Fig. 3, I have illustrated another form of my invention, in which the auxiliary supply pipe 30 is attached to a foot valve 40 of the hinged type. In this valve the intake orifice 41 is adapted to be closed by a hinged valve plate 42. The pipe 30, adapted to conduct fluid under pressure, communicates 25 with an inlet 43 directed toward the valve plate 42, as shown.

Having described my invention, I claim:

1. In a device of the class described, a motor, a centrifugal pump having a downwardly extending inlet pipe, and a discharge pipe, said pump affording continuous flow 30 of fluid therethrough during periods of in-operation thereof, a foot valve at the lower end of said inlet pipe, comprising a casing having an inlet orifice, a check valve for 35 having an inlet orifice, a check valve for

said orifice, a jet directed toward said check valve, an auxiliary fluid pipe connected with said jet, and means controlled independently of said pump motor for supplying fluid under pressure to said fluid pipe. 40

2. In a device of the class described, a motor, a centrifugal pump having a downwardly extending inlet pipe, and a discharge pipe, said pump affording continuous flow 45 of fluid therethrough during periods of in-operation thereof, a foot valve at the lower end of said inlet pipe, comprising a casing having an inlet orifice, a check valve for 50 said orifice, a jet directed toward said check valve into the chamber surrounding said inlet valve and above said valve, an auxiliary fluid pipe connected with said jet, and means controlled independently of said pump motor for supplying fluid under pressure to said fluid pipe. 55

3. The method of intermittently operating a centrifugal pump having a one way inlet valve and a discharge pipe whereby continuous flow of fluid is permitted through said pump and discharge pipe 60 which consists in introducing during periods of inoperation of said pump, a flow of fluid under pressure at a point above the inlet valve whereby the fluid in the system above said inlet valve is kept in constant 65 agitation.

In witness whereof, I hereunto subscribe my name this 25th day of January, A. D., 1922.

DON S. WILLEY.
